EMANUEL WOODINGS, OF OAKMONT, PENNSYLVANIA, ASSIGNOR TO WOODINGS-VERONA
TOOL WORKS, OF VERONA, PENNSYLVANIA, A CORPORATION OF PENNSYLVANIA

COMBINED TIE PLATE AND RAIL ANCHOR

Application filed April 16, 1932. Serial No. 605,572.

This invention relates to railway track construction, and particularly to a combined tie plate and fastening device adapted to receive and hold a rail on a tie.

- 5 8 An object of the invention is to provide in a single integral device a tie plate that will receive and seat the rail on a tie, between shoulders that prevent lateral movement of the rail, portions of the tie plate 10 being adapted to prevent the rail from lifting away from the plate, and, optionally, to clamp the rail thereon to prevent its longitudinal movement relative to the tie plate. More specific objects and advantages of the 15 structure will be apparent to those familiar with the art from the following specification.

Referring to the drawing, Fig. 1 is a plan view of a rail seated in a tie plate embodying 20 the preferred form of the invention; Fig. 2 is a vertical section through the rail and an end elevation of the tie plate and fastening device of Fig. 1 applied thereto; Fig. 3 is a view similar to that of Fig. 2, showing a 25 modification adapted to lock the rail against vertical removal from the plate but leaving it free as to longitudinal movement; Fig. 4 is a side view of the tie plate of Figs. 1 and 2, with a rail seated on the plate; Figs. 5 30 and 6 are plan views of other modifications; Fig. 7 is a vertical section through a rail with the tie plate of either Figs. 5 or 6 applied thereto; and Fig. 8 is a view similar to Fig. 4, with the modified tie plate of Fig. 6 35 applied to a rail.

In railway track construction rails are ordinarily seated upon tie plates which in turn are seated upon wooden ties embedded in the ballast of the road bed. Usually the 40 tie plates have a longitudinal retaining rib on one side against which the base flange of the rail abuts, the rail being fastened to the tie plate, and the tie plate in turn fastened to the tie, by means of spikes or screws 45 through the plate and having heads extending over the edges of the rail base.

Rails in track construction such as that above referred to, tend to creep in the direction of train travel thereon. To prevent this 50 creepage, rail anchors, or creep checks, are

usually applied to the rails at intervals. These anti-creep devices consist of some kind of clamp applied to the rail base and adapted to abut against the ties, or tie plates. The present invention combines in one device the 55 functions of the tie plate and separate rail anchors, with a reduction of cost, and an increase of efficiency.

In Figs. 1 and 2 there is illustrated a standard rail R, having the usual base flange 60 adapted to seat on a tie plate. The rail base has a flat bottom, and tapered upper sides leading to the intermediate web.

The tie plate shown comprises a base member 1 with comparatively high longitudinal 65 parallel shoulders 2, spaced apart a distance sufficient to receive snugly the rail base therebetween. At opposite ends these shoulders have longitudinal transverse under-cuts 3, preferably saw cuts, running transversely 70 longitudinally from the ends to a distance somewhat less than half the length of the tie plate, the cuts being positioned in a plane determined by the thickness of the rail base and the angle of the upper side thereof. The 75 cuts, when the rail is seated in the plate, preferably, but not necessarily, lie in extensions of the planes of the upper sides of the rail base, respectively.

After the rail is seated in the plate, locking 80 portions 4 above the cuts are bent inward laterally of the shoulder in a horizontal direction, as by a blow of a spike maul, so as to overlie and ride upon the inclined faces 5, 5, of the rail base, as shown in Figs. 1, 2, and 85 4.

As the ends of the locking portions 4 are bent horizontally inward the inclined under faces of these portions come into contact with the rail base, the angle of the inclined faces of the rail base and the underside of the projection, 4, 4, being substantially the same. Any further bending inward of the portions 4, after contact with the rail base, results in distortion of the metal, and applies a resilient clamping grip of the rail base between the 90 locking portions 4, and the body portion 1 of the tie plate. The rail is thus securely held by the plate against relative lateral, vertical and longitudinal movement. The plate itself may be attached to a tie T by spikes or 95 100

any suitable means, many of which are well known in the art. Since spikes or screws are not relied on with this plate to clamp the rail down, spike holes may be positioned near the outer edges of the plate, or other places remote from the rail edge. This helps 5 conserve the tie, and is an advantage compared to usual construction in which spikes are driven at the rail base edge. Since the spike holes may be located at any desired point in 10 the plate outside the shoulders 2 they are not here illustrated.

In Fig. 3 a modification is shown in that 15 the cuts 3a are so wide that the locking portions 4a may extend over the rail base materially without contact therewith. Consequently the rail seats in the tie plate 1a shown in Figs. 3 and 4, and is held against lateral and substantial vertical movement 20 by the locking shoulders of the tie plate, but is not clamped to restrict longitudinal movement.

In Fig. 5 the shoulders 2b instead of being 25 undercut as in Figs. 2 and 3, have vertical cuts, near the opposite ends of the shoulders. The cuts form end locking portions 4b which grip the rail to the tie plate when they are bent over against the rail base as shown in Fig. 7.

In Fig. 6 two vertical cuts are made in the shoulders 2c, and the intermediate portion 4c is bent over into contact with the rail base as 30 illustrated in Fig. 7. The degree of resilient clamping grip of the tie plate on the rail base 35 may be varied somewhat by the extent to which the locking portions 4, 4b, or 4c are driven inward over the rail base. But in all forms of the device, after the rail has been seated, and the locking portions forced in- 40 ward to overlie the rail base, the rail is locked to the plate and tie by integral portions of the tie plates, without the necessity of having spike heads contact with the rail base.

According to the provisions of the patent 45 statutes, I have explained the principle and mode of operation of my invention, and have illustrated and described what I now consider to represent its best embodiment. However, I desire to have it understood that, 50 within the scope of the appended claims, the invention may be practiced otherwise than as specifically illustrated and described.

I claim:

1. In railway track construction comprising 55 a tie and a rail, a plate member adapted to be positioned on the tie and under the rail and having parallel shoulders on each side of the rail seat, said shoulders having under- 60 cuts from opposite ends in extensions of the respective planes of the upper faces of the rail base, the parts of the shoulders above said cuts being adapted to be bent inward to overlie the rail base.

2. A tie plate adapted to seat a rail on a 65 tie in railway track construction, having par-

allel longitudinal shoulders adapted to form a snug seat therebetween for the rail base, the shoulders extending upward a distance materially greater than the thickness of the outer edges of the rail base, the upper end 70 portions of the shoulders being separated from the lower portions thereof by transverse cuts extending longitudinally and laterally into the shoulders from the ends thereof, the walls of the cuts being parallel to the 75 planes of the upper sloping sides of the rail base.

3. In railway track construction, a plate 80 adapted to seat on a tie and to receive a rail thereon, the plate having shoulders adapted to retain the rail base against lateral movement, the shoulders extending above the edges of the rail base and having transverse longitudinal under-cuts extending inward from the ends of the shoulders, whereby to furnish 85 portions adapted to be bent horizontally inward to overlie a rail base positioned on the plate.

4. In railway track construction, a plate 90 adapted to be positioned between a tie and a rail, the plate having a shoulder adapted to abut one side of the rail base, extending above the rail base, and having a transverse longitudinal under-cut extending inward from an end of the shoulder, whereby to furnish a portion adapted to be bent horizontally 95 inward to overlie a rail base seated on the plate.

5. In a railway track construction, a plate 100 adapted to seat on a tie and to receive a rail thereon, the plate having shoulders adapted to retain the rail base against lateral movement thereon, one of the shoulders extending above the rail base and having a transverse longitudinal under-cut extending inward 105 from an end of the shoulder, whereby to furnish a portion adapted to be bent horizontally inward to overlie a rail base positioned on the tie.

6. In railway track construction, a plate 110 adapted to be positioned between a tie and a rail, the plate having shoulders adapted to retain the rail base, the shoulders extending above the edges of the rail base and having transverse longitudinal under-cuts extending inward from one end of each of the shoulders, whereby to furnish portions 115 adapted to be bent horizontally inward to overlie a rail base seated on the plate.

In testimony whereof, I sign my name.

EMANUEL WOODINGS.
